UNITED STATES PATENT OFFICE.

HENRY ROBERTS, OF HARTFORD, CONNECTICUT.

ELEVATOR.

SPECIFICATION forming part of Letters Patent No. 252,801, dated January 24, 1882.

Application filed November 15, 1881. (No model.)

To all whom it may concern:

Be it known that I, HENRY ROBERTS, of Hartford, in the county of Hartford and State of Connecticut, have invented a certain new and useful Improvement in Elevators, of which the following is a specification.

The object I have in view is to provide doors for the vertical doorways of elevator shafts or wells which will be opened and closed automatically by the movement of the elevator-cage, and will be efficient and convenient in use; and my invention therein consists in the novel means employed by me for this purpose, as fully hereinafter explained, and pointed out by the claims:

In the accompanying drawings, forming a part hereof, Figure 1 is a vertical section of the elevator-shaft, the doors, and the cage; and Fig. 2, a view of the doors from the interior of the elevator-shaft, the weight-wells being uncovered to show the counter-weights.

Like letters denote corresponding parts in both figures.

A is an elevator shaft or well, and B the cage moving therein.

C' C² C³ C⁴ represent the vertical openings from the several floors of the building into the elevator-shaft. Four openings are shown; but the number will correspond with the stories of the building, and may be more or less than four. These four openings or doorways are closed by six doors, D' D² D³ and E' E² E³, which slide vertically in three sets of ways or grooves, a' a² a³, formed in vertical pieces F F', secured within the elevator-shaft at the sides of the doorways. The doors D' D² D³ slide in the ways a' a² a³ from the top of the shaft downwardly and close the openings C' C² C³. These doors drop by their own weight and are raised by the elevator-cage. The doors D' D² are arrested opposite openings C' C² by stops b' b², placed in the grooves a' a², while door D³ is arrested opposite opening C³ by a stop, b³, on the side of piece F', the door being provided with an arm, b⁴, to engage said stop. The elevator-cage is provided on its top with an arm, G, which engages with the bottom edge of the door D³ and raises the same. This door D³ has a cleat, c, on its bottom edge, which 50 catches the lower end of door D² and carries D² up with it. The cleat c, however, will not

reach D', since it must be made to clear the inward extensions, d d', of the sills to doorways C² C³, which extensions are provided to fill up the space between the sills and the doors, for which purpose the cleat c is also used. The door D' has at or near its upper end a block, e, which is struck by door D², causing D' to be carried up with D³ and D².

The doors E' E² E³ slide upwardly in the grooves a' a² a³ from the bottom of the elevator-shaft or well. They are raised to positions in doorways C' C² C³ by means of counter-weights H' H² H³, which move in wells I, and are connected with the doors by wire or hemp ropes or cords or by chains passing over pulleys in the pieces F F'. The doors E' E² are arrested in their upward movement opposite doorways C⁴ C³, respectively, by stops f' f², situated in the grooves a' a², below stops b' b², while door E³ is arrested in doorway C² by a stop, f³, on piece F, the door being provided with an arm, f⁴, to engage said stop.

The elevator-cage has a projecting sill, K, which works close to the extensions d d' of the door-sills of C² C³, and strikes the upper ends of doors E³ E², pushing them down as it descends. The door E' has a block, h, which is struck by door E², causing E' to be pushed down with E³ and E². By means of these two sets of doors the doorways will be opened and closed automatically by the movement of the cage. The doors D³ and E³ have their stops outside of groove a³ on pieces F F', because each door passes the stop of the other door in its movement.

It will be seen that with the arrangement shown of two sets of vertical doors each set has one less door than the full number of doorways. Each vertical doorway is always closed by a door, or the elevator-cage itself is in position opposite the same, or it is partly closed by a door and partly filled by the cage, as is the case in the opening and closing of the doorways by the movement of the cage. For this reason my invention provides a safeguard against the many accidents which occur by reason of the doorways to elevator-shafts being left open. The doors being automatically operated by the elevator-cage, they do not require any attention. The doorways are made the full width of the elevator-shaft, and so are

the doors, which will permit, in case of passenger-elevators, of the rapid filling and emptying of the cage—an advantage in large buildings or public places, where the elevators are crowded and delay is caused by small exits and entrances.

It will be understood that any suitable material may be used for the several parts described. Any number of counter-weights can also be employed to raise the doors of the lower set. Two counter-weights for each door are preferred, in order to balance the door and make it work smoothly, although, for clearness, only one is shown in the drawings.

The several parts can be changed in detail of construction and arrangement without departing from the spirit of my invention.

I am aware that it is old to provide an elevator-shaft with two sets of horizontal hatches, one above and the other below the elevating-platform, those below the elevating-platform being depressed thereby and raised into position by counter-weights, while those above

said platform are raised thereby and drop into position by their own weight.

25

What I claim is—

1. In elevators, the combination, with the elevator shaft or well having vertical doorways and the elevator-cage, of two sets of vertical doors, one above and one below the cage, the doors above the cage being raised thereby and dropping by their own weight, while those below the cage are pushed down thereby and raised by counter-weights, and stops for arresting the doors of each set in succession, substantially as set forth.

2. In elevators, the elevator-cage having projections, in combination with the two sets of doors sliding in vertical ways and raised and pushed down respectively by the projections on the cage, substantially as set forth.

HENRY ROBERTS.
